Paul Howard, Jacksonville, Fla.

Application March 21, 1944, Serial No. 112,977

Term of patent 7 years

(Cl. D74—1)

To all whom it may concern:

Be it known that I, Paul Howard, a citizen of the United States, residing at Jacksonville, in the county of Duval, and State of Florida, have invented a new, original, and ornamental Design for a Holder for Receipt Pads or the Like, of which the following is a specification, reference being had to the accompanying drawing, forming part thereof.

I claim:

The ornamental design for a holder for receipt pads or the like, as shown.

PAUL HOWARD.
